UNITED STATES PATENT OFFICE.

ARTHUR D. RIZER, OF ELGIN, ILLINOIS, ASSIGNOR TO THE NATIONAL ELECTRICAL MANUFACTURING CO., OF ELGIN, ILLINOIS, A CORPORATION OF ILLINOIS.

CIRCUIT-CLOSING DEVICE.

1,034,510.

Specification of Letters Patent. Patented Aug. 6, 1912.

Application filed August 4, 1910. Serial No. 575,424.

To all whom it may concern:

Be it known that I, ARTHUR D. RIZER, a citizen of the United States, residing in the city of Elgin, county of Kane, and State of Illinois, have invented certain new and useful Improvements in Circuit-Closing Devices, of which the following is a specification.

This invention relates to circuit closing devices and refers more particularly to contact devices adapted to automatically close a signaling circuit as a trolley car is passing by a certain point.

Among the salient objects of the invention are to provide a construction of the above character in which the contact devices are controlled by the passing trolley wheel in such a way as to insure the closing of the signaling circuit for a sufficient length of time to obtain reliability in the operation of the signal; to provide a construction in which the contact devices are normally held open against the action of a spring by means of a weighted bar clamped to the trolley wire, the bar being raised by a passing trolley wheel; to provide a construction in which that portion of the trolley wire to which the bar is connected is itself secured to a rigid supporting member to prevent the trolley wire as a whole becoming tightened from weather conditions and thus accidentally raise the bar and close the signaling circuit; to provide a device characterized by simplicity and economy of construction and freedom and reliability of movement and which is adapted to be mounted above a trolley wire by means of the usual supports; to provide a construction in which the contact devices may be suitably inclosed in a housing to protect them from weather conditions and in general to provide an improved construction of the character referred to.

The invention consists in the matters hereinafter described, and more particularly pointed out in the appended claims.

In the drawings Figure 1 is a fragmentary side elevation of my invention mounted upon the trolley wire. Fig. 2 is a fragmentary top plan view of the same. Fig. 3 is a fragmentary enlarged vertical sectional view of the circuit closer. Fig. 4 is a horizontal sectional view of the same. Fig. 5 is a top plan view of a somewhat modified construction. Fig. 6 is a fragmentary vertical sec-

tional view of an enlarged section of the construction shown in Fig. 5.

Referring to the drawings, 1 designates as a whole a trolley wire above which is mounted to extend horizontally a frame support 2 of channel or trough shape form, as shown more clearly in Fig. 3, and secured to the trolley wire by means of suitable clamps 3. This frame is also supported from the usual pole 3' mounted adjacent to the track by means of a cross arm 4 carried by the pole and end cables 5, 5 and the central cable 6. One end of each cable is suitably secured to the frame support as shown at 4'. The poles 3' are mounted close to the track, as is usually the case in trolley systems although the particular manner of supporting the frame is not material in the broader aspects of the invention. In each cable is inserted an insulating piece 8 in the usual manner.

The foregoing arrangement is such that the channeled supporting member 2 is rigidly secured to the trolley wire on either side of the contact devices in such a way as to prevent the wire from being tightened during cold or hot weather. Difficulty has heretofore been experienced in devices of this general character because of this tightening of the trolley wire with the result that the signaling circuit is accidentally closed. The present construction obviates this difficulty.

Upon the central portion of the frame member 2 is mounted a circuit closer designated as a whole 9. Describing this instrument, upon the upper face of the frame 2 is mounted a pair of spaced apart ears 10 apertured to receive a journal pin 11 which, in the present instance, takes the form of a headed bolt secured to the ears by means of a nut 12 and washer 13. Upon this pin is pivotally mounted a pair of opposed contact arms 14, 14' curved as shown and provided with contact devices 15, 16, one of which is forked as shown at 15'. These devices are adapted to contact with each other when the arms are swung inwardly into closed position. The contact 16 of the arm 14' is insulated from the trolley wire and main body of the circuit closer by means of an insulating block 17. To this contact 16 is connected the wire 18 leading to any suitable signaling circuit not shown. It will be understood, of course, that the circuit extends through the trolley wire and contact

arms when closed to the wire 18 and signaling circuit to ground. These arms 14, 14' are normally held in open position by means of a bar 19 connected to the arms by means of chains 20. The bar 19 is in turn rigidly connected to the trolley wire by means of a clamp 21. In order to protect the circuit closer from the weather I provide a box like cover member 22 riveted as shown at 23 to 10 the frame member 2 and apertured as shown at 24 to permit of the chains 20 being attached to the arms 14, 14'. The central portions of the arms are connected by means of a coiled contractile spring 25 which tends to 15 normally force the contact members into closed position. The tension of this spring, however, is not sufficiently strong to lift up the trolley wire and bar 19.

In Figs. 5 and 6 I have shown a somewhat modified construction which is more particularly adapted for use with trolleys in which the track is located in the center of the street. Referring to these figures the trolley wire 1' is supported in the usual 20 manner by the cross cables or guys 1'' secured to the posts 26 at opposite sides of the street. The cross supports 1 are insulated as usual as shown at 26'. Midway between the posts 26 and above the trolley wire 25 1' is supported a plate like frame member 2' to each corner of which is connected a supporting cable 27 as shown at 28. The other end of each of these cables leads diagonally to one of the posts 26 and is fixed 30 thereto. Each cable is also insulated as shown at 29. Upon the plate 2' is mounted a circuit closer 9 which is exactly similar to the circuit closer hereinbefore described. The arms 14 as before are connected by the 35 chains 20 to the bar 19 carried by the clamp 21 mounted on the trolley wire 1'. In order that the chains 20 may be attached to the arms 14, 14' the frame plate 2' is apertured as shown at 30.

The operation of the device may be 40 briefly described as follows: Normally the sag of the trolley wire and the weight 19 will hold the contact arms in open position against the action of the spring 25. When, 45 however, the trolley wheel approaches the shoe 21 it will raise the wire and bar 19 whereupon the arms 14, 14' will be released, and at once be automatically closed by means of the spring 25. Inasmuch as the 50 trolley wheel will raise the wire for an appreciable length of time as it passes by the shoe 21, the contact devices will be closed for a sufficiently long time to insure of the closing of the signaling circuit and operation 55 of the signal. As soon as the trolley wheel has passed away from the portion of the trolley wire adjacent the shoe 21, the latter will drop back to its normal position 60

to gravity and the contact devices will be pulled into open position. The construction is comparatively simple and inexpensive and in addition has the advantage of absolute reliability of operation as long as the parts do not break. The danger of breakage is reduced to a minimum as there is no delicate or complicated mechanism to get out of order.

The invention is not limited to the details of construction shown except as set forth in the appended claims.

I claim as my invention:

1. In a circuit controlling device, the combination with a trolley wire, of a bar or frame member mounted above the same, clamps near either end of the frame member and rigidly connected to the trolley wire whereby a short section of trolley wire is rigidly connected to the frame member, contact devices, means for automatically closing said devices, a controlling member for normally holding said devices in open position, said controlling member being connected to the trolley wire at a point intermediate the clamps of the frame member whereby the controlling member is raised to release the contact devices when the wire is raised by a passing trolley wheel.

2. In a circuit controlling device, the combination with a trolley wire, of a bar-like frame member extending above the same and rigidly secured adjacent its ends to the trolley wire, a pair of opposed contact arms pivotally mounted above the trolley wire, contact devices carried by said arms, one of said devices being normally insulated from the trolley wire, a spring for automatically closing the contact devices, and means for normally holding said contact devices in open position comprising a bar suspended from said contact arms and connected to and depressing the trolley wire at a point intermediate the connections of the frame member with the trolley wire.

3. In a circuit controlling device, the combination with a trolley wire, of a bar-like frame member suspended above the trolley wire, clamps adjacent either end of the frame member and rigidly connected to the trolley wire whereby a relatively short section of said trolley wire is rigidly connected to the frame member, contact devices mounted above the frame member, means for automatically closing said contact devices and means connected to the trolley wire at a point between said clamps for holding said contacts normally in open position.

ARTHUR D. RIZER.
